UNITED STATES PATENT OFFICE.

THOMAS L. McKEEN, OF EASTON, PENNSYLVANIA.

FRICTION DRAFT AND BUFFING GEAR.

SPECIFICATION forming part of Letters Patent No. 761,584, dated May 31, 1904.

Application filed January 15, 1904. Serial No. 189,075. (No model.)

To all whom it may concern:

Be it known that I, THOMAS L. McKEEN, a citizen of the United States, residing at Easton, in the county of Northampton and State 5 of Pennsylvania, have invented new and useful Improvements in Friction Draft and Buffing Gears, of which the following is a specification.

This invention relates to railway-car friction draft and buffing gears of the type described in United States Letters Patent, granted to me December 2, 1902, No. 714,815, and which involves, besides the usual coil-springs, bowed flat springs or spring-plates which are 10 arranged longitudinally relative to the draft and buffing gear and are strained or compressed laterally and exert their pressure against friction devices and act in conjunction with the coil-springs to ease and absorb the 15 draft and buffing strains and shocks.

The object of the invention is to produce a friction draft and buffing gear of this type which combines great spring and friction capacity with extreme compactness and simplicity and in which a spring box or cylinder 20 is provided which incloses and protects the spring and friction devices from rain, snow, and dirt and relieves the car-frame and connections for the gear from all lateral strain.

In the accompanying drawings, Figure 1 is 25 a longitudinal horizontal section, partly in plan, of a friction draft and buffing gear embodying the invention. Fig. 2 is an elevation, partly in vertical section, thereof. Figs. 3 and 4 are transverse vertical sectional elevations thereof in lines 3 3 and 4 4, respectively, Fig. 1. Fig. 5 is a longitudinal horizontal section, partly in plan, of a platform-buffer embodying the invention.

Like letters of reference refer to like parts 30 in the several figures.

A represents cheek-plates of any usual or suitable construction, which are secured to the draft-sills *a* and are provided with inwardly-extending shoulders or stops *a'*, and B an inclosing or protecting box, preferably cylindrical in form, which is arranged between the cheek-plates and is provided with laterally - projecting horizontal wings or

flanges *b*, which extend between inwardly-projecting horizontal flanges *c* at the tops of the cheek-plates, and horizontal carrying irons or bars *d*, secured to the lower portions of the cheek-plates. The wings or flanges on the box serve as supporting and guiding means, 50 as well as strengthening-ribs, for the same, and their rear ends are connected to the box by transverse vertical plates or portions *e*, constituting shoulders or abutments, which are arranged in front of and coöperate with 55 the stops on the cheek-plates to limit the rearward movement of the box and transmit the buffing-shocks to the cheek-plates and draft-beams. The cylindrical form of the box is preferred, as it properly centers and holds 60 the coil draft and buffing springs and lends great strength to the box.

F represents the draw-bar or coupler-stem, having secured to its rear end the usual yoke or loop *G*, which surrounds the spring-box to 65 connect the draw-bar therewith.

H represents a front follower or plate arranged transversely in the front portion of the loop against the rear end of the draw-bar, with its ends extending in rear of and coöperating with the front stops of the cheek-plates in drawing the car. The follower is provided with a rearwardly - projecting reduced portion *h*, which enters and is adapted 70 to slide in the contracted front end of the 75 spring-box. The follower constitutes a closure or stopper for the spring-box and effectually prevents the entrance thereto of rain, snow, dirt, and the like, and thus adds greatly to the efficiency of the gear.

I represents an intermediate or central follower loosely confined in the central portion of the spring-box, which latter itself constitutes or takes the place of the usual rear follower and moves forwardly with the draw-bar 80 and yoke in drawing the car.

K *k* represent respectively, outer and inner coil draft and buffing springs arranged in the rear portion of the spring-box between and bearing at their ends against the intermediate follower and rear end of the spring-box. The portion of the box containing the coil-springs is contracted to properly center 85 90 95

and retain the coil-springs and also to form an internal annular shoulder l at the central portion of the box.

M represents bowed spring-plates or flat springs arranged longitudinally and centrally in the front portion of the spring-box between and bearing at their ends against the front and intermediate followers.

N represents wear or friction plates arranged on opposite sides of the spring-plates and held from longitudinal movement in the spring-box by engagement at their opposite ends with the internal shoulder l and the inwardly-extending flange or lip n at the front end of the box.

The friction-plates are provided at their inner or adjacent sides with inclined friction-faces n' , arranged in stepped order, and a laterally-movable wedge-plate O is arranged between each friction-plate and the spring-plates and provided with corresponding inclined faces on its outer side, which bear on the inclined faces of the friction-plates. The wedge-plates are confined between and movable with the front and rear followers and are shorter than the friction-plates, so that they are supported at both ends as well as centrally by the inclined faces of the friction-plates, and they cannot, therefore, be bent by the lateral pressure thereon in the use of the device. This arrangement of the inclined faces also gives greater friction surface.

When the draw-bar and yoke are pulled forward in drawing the car, the spring-box is also carried forward, and as the front follower is held stationary by its engagement with the stops on the cheek-plates it holds the spring-plates and wedge-plates and intermediate follower from longitudinal movement also. The coil-springs are thus compressed, and the wedge-plates are moved laterally by reason of the engagement of their inclined faces with the inclined faces of the friction-plates, thereby compressing or straining the spring-plates also and creating friction between the wedge and friction plates. In buffing the spring-box is held stationary by the stops on the cheek-plates, and the front and intermediate followers, with the spring and wedge plates, are moved rearwardly to similarly compress or strain the coil-springs and spring-plates.

The spring-plates are nested or all arranged parallel, as shown, for this arrangement requires less space crosswise of the spring-box and permits the use of a spring-box no larger than required for the ordinary coil-spring gear, and the capacity of the spring-plates is equal or nearly equal to twice the number of spring-plates arranged part facing one way and part the other way, and only one-half as great a lateral movement of the wedge-plates is required to fully strain all of the spring-plates. The friction or wear plates are loosely

confined in the spring-box and can be removed 65 when worn and replaced by new ones, thereby saving the spring-box from wear and greatly increasing its life. All of the parts of the spring-gear are contained in and protected by the spring-box of small diameter, 70 which does not increase the space occupied by the gear, but relieves the car-frame and attaching devices from all lateral strain. The device consists of but few parts, which are of such construction that it is practically impossible for an unskilled workman to improperly assemble them. 75

Fig. 5 shows the above-described arrangement of the spring-plates, wedges, and friction-plates applied to a platform-buffer. B' 80 represents the spring-box, which is fixed to the car-frame between the car and platform end sills; F', the central stem of the buffer; H' and I', the followers; M', the spring-plates arranged in the relation before described between the followers; N', the friction-plates, which are held from longitudinal movement in the spring-box by inwardly-projecting stops thereon, and O' the wedge-plates. This construction operates in buffing in the same 90 manner as the draft and buffing gear above described.

I claim as my invention—

1. The combination of a spring-box, two followers movable therein, springs arranged 95 between one of said followers and the end of the box, spring-plates arranged longitudinally centrally in the box between said followers, friction-plates in said box at opposite sides of said spring-plates and each having an inclined face, and wedge-plates between said inclined faces and said spring-plates, substantially as set forth.

2. The combination of a movable spring-box, guide and stop devices therefor, a draw-bar connected to said spring-box and movable relative thereto, two followers movable in said box, springs arranged in said box between one end thereof and one of said followers, spring-plates arranged longitudinally centrally in the box between said followers, laterally-movable wedge-plates between said followers at opposite sides of said spring-plates, means acting upon a relative movement of said wedge-plates and box to force 115 the wedge-plates against said spring-plates, and friction means between said spring-plates and box, substantially as set forth.

3. The combination of a movable spring-box, guide and stop devices therefor, a draw-bar connected to said spring-box and movable relative thereto, two movable followers, coil-springs arranged in said box between one end thereof and one of said followers, spring-plates arranged longitudinally centrally in the box 125 between said followers, lateral movable wedge-plates between said followers at opposite sides of said spring-plates, and friction-plates be-

tween said spring-plates and the box and each having a plurality of inclined faces coöperating with said wedge-plates to force the latter against said spring-plates upon a relative 5 longitudinal movement of the wedge-plates and spring-box, substantially as set forth.

4. The combination of a spring-box, having an open end, a follower having a portion which extends into the open end of said box 10 and constitutes a closure therefor, and spring and friction devices inclosed by said box, substantially as set forth.

5. The combination of a movable spring-box having an open end, means for limiting 15 the movement of said spring-box, a draw-bar connected with said box to move the latter with it in one direction and movable in the opposite direction independently of said box, a follower movable with said draw-bar and 20 having a part extending into the open end of said box and constituting a closure therefor,

and spring and friction devices inclosed in said box, substantially as set forth.

6. The combination of a spring-box, two followers movable therein, springs arranged 25 between one of said followers and the end of said box, spring-plates arranged longitudinally in the box between said followers, friction-plates in said box and each having a plurality of inclined faces, and wedge-plates 30 each having inclined faces coöperating with the inclined faces of said friction-plates and which are pressed against said friction-plates by said spring-plates, substantially as set forth.

Witness my hand this 31st day of December, 1903.

THOMAS L. McKEEN.
